(57) **CLAIM**

The ornamental design for a box, as shown and described.

DESCRIPTION

The file of this patent contains at least one drawing executed in color. Copies of this patent with color drawings will be provided by the Office upon request and payment of the necessary fee.

FIG. 1 is a front, top, right perspective view of a first embodiment of a box, showing the new design;

FIG. 2 is a rear, top, left perspective view thereof;

FIG. 3 is a front view thereof;

FIG. 4 is a rear view thereof;

FIG. 5 is a left side view thereof;

FIG. 6 is right side view thereof;

FIG. 7 is a top plan view thereof;

FIG. 8 is a bottom plan view thereof;

FIG. 9 is a front, top, right perspective view of a second embodiment of a box, showing the new design;

FIG. 10 is a rear, top, left perspective view thereof;

FIG. 11 is a front view thereof;

FIG. 12 is a rear view thereof;

FIG. 13 is a left side view thereof;

FIG. 14 is right side view thereof;

FIG. 15 is a top plan view thereof; and,

FIG. 16 is a bottom plan view thereof.

The broken lines of even length illustrate portions of the box and form no part of the claimed design.

The Mounjaro logo forming part of the claimed design is a registered trademark of Eli Lilly and Company.
